UNITED STATES PATENT OFFICE.

CARLETON ELLIS, OF MONTCLAIR, NEW JERSEY.

PROCESS OF HARDENING OIL.

1,294,068.

Specification of Letters Patent. Patented Feb. 11, 1919.

Application filed February 2, 1916. Serial No. 75,769.

To all whom it may concern:

Be it known that I, CARLETON ELLIS, a citizen of the United States, and a resident of Montclair, in the county of Essex and State of New Jersey, have invented certain new and useful Improvements in Processes of Hardening Oil, of which the following is a specification.

This invention relates to a method of 10 hydrogenating fatty oils or other similar treatment with gases especially in the presence of catalytic material and relates particularly to the hydrogenation of comparatively thin layers of oil by the rapid circulation therethrough of a strong current of hydrogen, especially in conjunction with a 15 method of regenerating the heat withdrawn from the hydrogen gases during the process of purification; all as more fully hereinafter 20 described.

The drawings which are diagrammatic show apparatus for carrying out my present invention. Figure 1 shows partly in vertical section and partly in elevation an 25 organization of apparatus adapted for carrying out the process hereof, and Fig. 2 shows a similar view of a modified form of apparatus.

In Fig. 1 of the drawings 1 is a horizontal cylindrical tank, the upper part of which is shown in longitudinal elevation and the lower part is shown in longitudinal section, 2 is a coil arranged for the admission of steam or hot oil for heating the contents 30 of the tank as may be desired and also for cooling purposes by the circulation of cold water therethrough when the temperature increases beyond the desired point due to exothermic reactions taking place in the oil during the hydrogenation process.

3 is a distributor for hydrogen gas which may be in the form of a single pipe as shown or preferably when using tanks of considerable length may be formed of a number of 45 pipes terminating at different points in the bottom of the hydrogenating tank, each terminus being equipped with a rose or similar device so that the entire body of oil is thoroughly stirred by the fairly uniform passage of the hydrogen gas therethrough. 50 4 is a dome for collecting gases. 5 is a blow-off pipe fitted with a valve. 6 is a tank fitted with an agitator, the driving pulley of which is shown at 7, in which tank the oil and catalyst are mixed and are run

therefrom by the pipe 8 into the treating tank 1. The pipe 9 leads from the top of the dome 4 and communicates with the pipes 10 and 15. The pipe 10 communicates directly with the pump 12. The pipe 15 serves to connect the pipe 9 with the heat regenerator 14. The outlet from the pump 12 communicates with the regenerator by the pipe 13. The pipe 16 extends to the purifiers 17, 18 and 19 and from the latter 60 the pipe 20 communicates with the regenerator 14. Intermediate the pipe 20 is a pump 21 which may be of the positive pressure type as indicated or may be a steam pump similar to that shown at 12. In place of 65 using a steam pump such as the pump 12, a positive pressure blower likewise may be used at that point. The regenerator 14 consists of a shell or cylindrical chamber 70 inclosing the pipe through which the cold hydrogen enters the treating tank 1. The 75 hot hydrogen is allowed to flow through the annular space between this pipe and the cylindrical jacket thereby heating the gas about to enter the tank 1.

The purifiers are filled with caustic soda solution or lumps of dry caustic soda or soda lime and the like. A solution of caustic soda may be used in the tank 17, a solution of permanganate of potash may be 85 introduced into the tank 18 and the tank 19 may contain calcium chlorid or soda lime for drying purposes. A considerable amount of water is removed from the oil by the hydrogen gas and this should be eliminated to a large extent before the unused 90 hydrogen is returned by the cyclic circuit.

A comparatively thin layer of oil is placed in the tank 1 and into this oil the requisite amount of catalytic material such as finely-divided nickel is introduced or the mixture of oil and catalyst is run into the tank from the tank 6. The layer of oil ordinarily should not be more than about two feet in thickness, in order to secure the full 95 benefit of the hydrogen treatment. Under these circumstances a comparatively low hydrogen head or pressure is sufficient to maintain the hydrogen current at rapid travel through the oil so that hydrogenation 100 takes place quickly and effectively and without the difficulties attendant on the use of strong pressures of hydrogen. During the first hour or so that the oil is being 105 treated with hydrogen, water and other 110

products are formed in considerable amount and a considerable proportion of the hydrogen gas is shunted through the purifiers 17, 18 and 19. This gas is cooled by purification and on its return is passed through the regenerator thereby heating it up to the requisite temperature. Thus hot instead of cold hydrogen enters the body of oil and this heating is desirable when hydrogenating shallow layers of oil because hydrogen is a poor conductor of heat and when traveling as a strong current through a body of the oil may well pass entirely through the oil without becoming heated sufficiently to react readily.

A portion of the hydrogen therefore is preferably circulated through the purifiers while another portion may go directly back to the hydrogen tank, the division of the gases depending upon the stage of the operation and consequent degree of impurity. A certain small impurity does no harm but when it becomes larger in amount the catalyst is liable to be affected and the operation hindered.

When it is not desired to use the regenerator the valve of the pipe 15 may be closed and the hydrogen gas drawn directly through the pipe 10 to the pump 12.

30 Instead of having a long cylindrical tank placed in a horizontal position with the hydrogen delivered along a vertical plane passing through the axis whereby a current of hydrogen is produced along such plane resulting in an effective circulation of the oil, it is possible to use large flat tanks, as shown in Fig. 2, the height of the oil in which is much less than the diameter of the tank and to locate in different parts of the 35 bottom of the tank a number of distributors so that a comparatively thin layer of the oil, ordinarily not more than two to four feet, is treated in this manner.

Referring now to Fig. 2, the tank 31 provided with steam heating coil 32 may be used, the hydrogen being introduced through pipe 33, perforated as illustrated. This tank may be provided with a dome 34, an exhaust pipe 35, oil inlet 38. 39 represents the outlet 40 for unabsorbed hydrogen, which after passing through a purifying and drying system, as in Fig. 1, may be again introduced at 33. An oil draw off pipe is shown at 40. The treatment of a body of substantially greater 45 breadth than height overcomes any undesirable foaming or "puking" while at the same time giving good gas contact. Furthermore the quantity of oil treated is independent of the depth or height of the oil 50 layer, which is most advantageous. The en-

tire body of gas may be purified in a continuous manner or any part thereof.

What I claim is:—

1. The process of treating oil which comprises circulating a current of hydrogen gas 65 through a comparatively shallow layer of a fatty oil containing a finely-divided catalyst, in collecting the unabsorbed gas, in passing a portion thereof through a purifying agent, in combining the purified portion with the residual unpurified portion and in passing the mixture as a cyclic current through said layer of fatty oil.

2. The process of treating oil which comprises circulating a current of hydrogen gas 75 through a comparatively shallow layer of a fatty oil containing a finely-divided catalyst, in collecting the unabsorbed gas, in passing a portion thereof through a purifying agent, in combining the purified portion with the residual unpurified portion, in preheating the mixture and in passing said mixture as a cyclic current through said 80 layer of fatty oil.

3. The process of treating oil which comprises circulating a current of hydrogen gas 85 through a body of a fatty oil containing a finely-divided catalyst, the breadth of said body being substantially greater than the height thereof, in collecting the unabsorbed 90 gas and in passing a portion through a purifying agent, in combining the purified portion with the residual unpurified portion and in passing the mixture as a cyclic current through the layer of fatty oil.

4. The process of treating a bulk of oil which comprises subjecting the same to the action of hydrogen-containing gas in the presence of the catalyst, drawing off the unabsorbed gas and reintroducing same into 100 the oil, drying and purifying a relatively large part of the hydrogen-containing gas so withdrawn and returned during the first part of the operation, and purifying and drying not more than a small part thereof 105 during the later stages of the process.

5. In the hydrogenation of a bulk of oily material by circulating a hydrogen containing gas in contact therewith, in the presence of the catalyst, step of drying and 110 purifying a relatively large part of the hydrogen so circulated during that part of the process where considerable quantities of water are formed, and drying and purifying not more than a small portion of the hydrogen so circulated during that part of the process wherein only small amounts of water are formed.

CARLETON ELLIS.
